UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

LET-OFF FOR TERRY LOOMS.

Application filed February 23, 1924. Serial No. 694,557.

This invention relates to the terry loom such as commonly employed for weaving double pile fabrics employed in the manufacture of Turkish towels. It is important in the weaving of such fabric that there shall be woven sections of plain fabric as well as sections of pile fabric. These sections are alternated in stripes as desired and the width and position of the sections is usually determined by a pattern mechanism which automatically governs the change from plain to terry weaving and vice versa. In the terry loom there are two sets of warps. One set is carried by and runs off from a warp beam such as employed in any loom. The other set known as the terry warps is carried by and runs off from a separate terry warp beam and these terry warps form the loops of the pile fabric.

The present invention has for its chief object the provision of means for effecting the control of the terry warps so as to secure satisfactory results especially in the weaving of the plain sections of the fabric.

The object of the invention is further to provide a friction let-off means for the terry warp beam which shall exert an intensified or extra amount of friction during the weaving of the plain sections of fabric and thus insure an even and regular quality of plain weaving.

The object of the invention is further to provide means for controlling the tension on the terry warps during plain weaving so as to make it substantially the same as the tension upon the ground warps during plain weaving and thus insure a regular plain weave.

The object of the invention is further to provide means for insuring that the terry loops shall be maintained of uniform and full length to the end of the zone of terry weaving and shall not decrease in length adjacent the zone of plain weaving.

The object of the invention is further to provide an actuator for effecting the intensification of the amount of friction on the terry warp beam which shall not be subjected to any strain due to the normal or predetermined amount of friction on the terry warp beam imposed during terry weaving.

The object of the invention is further to provide a combination of a friction let-off for the terry warp beam and a positive let-off for the terry warps together with means

acting to render the positive let-off active and to cause the friction let-off to exert a predetermined amount of friction upon the full forward stroke beat of the reed for forming the terry loops, to cause the friction let-off to exert the said predetermined amount of friction and to render the positive let-off inactive during the partial forward strokes of the reed in terry weaving, and to cause the friction let-off to exert a greater amount of friction and to render the positive let-off inactive during plain weaving.

These and other objects and features of the invention will appear more fully from the accompanying description and drawings and will be particularly pointed out in the claims.

The invention in its preferred form is shown as applied to a familiar type of terry loom such, for example, as that illustrated in the patent to Merrill No. 1,322,715, November 25, 1919. As this type of loom is well known and familiar to those skilled in the art it is only necessary herein to illustrate and describe such a loom in so far as it is particularly concerned with the present invention.

In the drawings:

Fig. 1 is a front elevation of the end of the terry warp beam, its support, and certain of the mechanism associated therewith and necessary to a disclosure of the invention.

Fig. 2 is a side elevation of a portion of the construction shown in Fig. 1.

Fig. 3 is a side elevation partially broken away and partially in vertical cross section showing the rear portion of the loom.

Fig. 4 is a detail in side elevation showing the opposite end of the terry warp beam.

The loom comprises the usual side frames 1. These side frames rest upon the floor 2 and are connected by the usual girders and support the usual shafts and rods.

The warp beam 3 carrying the ground warps is supported by its shaft 4 at the rear of the loom frame in the usual manner. The ground warps 5 extend from this warp beam over the usual whip roll 6 forward through the usual harnesses, reed, and so forth (not shown) to the front of the loom. The control of and tension upon the ground warps 5 is provided by any suitable mechanism such as employed in any regular loom.

Standards 7 and 8 extend up from the side frames at the rear of the loom. These standards at the top are provided with roller bearings 9 upon which rest the trunnions 10 of the terry warp beam 11. The terry warps 12 extends from the terry warp beam downwardly through a positive let-off mechanism of a type similar to that shown in the patent to Davis No. 1,322,671, November 25, 1919, and then forwardly along with the ground warps.

In this type of loom the terry weaving is effected by varying the forward extent of the beat up movement of the reed. For several picks the reed has only a partial forward stroke toward the fell of the cloth so that a gap is left between the picks and the fell. The reed is then given a full forward stroke to beat up the several picks at once. When this full beat up of the reed takes place the terry warps are under a predetermined but slight tension and are usually positively fed forward or let off from the warp beam whereas the ground warps remain under the usual tension. Hence the portions of the terry warps which are between the group of picks and the fell of the cloth are looped on both sides of the fabric as the full beat up of the reed occurs. When a section of plain weaving is made the reed has its full beat up movement following each pick and hence no loops are formed in the terry warps. But difficulty has been experienced in making a perfect plain weave because of the inequality of tension between the terry warps and the ground warps. The present invention provides for securing the requisite tension on the terry warps to correspond with that on the ground warps and thus insure a regular and perfect plain weave while at the same time it provides for or permits the requisite tension and let-off of the terry warps during terry weaving.

It is particularly desirable that the terry loops shall be maintained of the same length or height throughout each zone of terry weaving. Heretofore difficulty has existed in this respect when the change takes place particularly from terry weaving to plain weaving because the terry loops have been drawn down or shortened. The present invention insures that the terry loops shall remain of the same length clear up to the zone of plain weaving and shall not be shortened or drawn down when the change takes place.

Various mechanisms may be provided for giving the partial and full forward strokes to the reed and for the purpose of disclosing the present invention it is assumed that such means as shown in the Merrill patent above mentioned are to be used. In that construction the control of the change from plain weaving to terry weaving and vice

versa is effected through a pattern mechanism including the pattern chain 13. An actuator 14 is pivoted at 15 and has a connector 16 which extends to and controls the beat-up motion. It is assumed that when 70 a riser 17 of the pattern chain holds the actuator 14 elevated the beat-up motion functions to perform plain weaving and that when the riser 17 passes from beneath the actuator 14 allowing it to fall to the position shown in dotted lines in Fig. 1, the beat-up motion functions to perform terry weaving. 75

In the construction illustrated the terry warps are under the control of two separate 80 mechanisms, first, a positive let-off mechanism of the type shown in the Davis Patent 1,322,671, above mentioned, and second, a friction let-off which acts to exert a predetermined constant amount of friction during 85 terry weaving and a greater amount during plain weaving.

The positive let-off mechanism is located between the terry warp beam and the reed. This mechanism, which may be of any suitable construction, is shown in Fig. 3 as generally similar to that of the before mentioned Davis Patent No. 1,322,671. The terry warps 12 run from the terry warp beam under an idler roll 18 and thence 90 around the rough surfaced let-off roll 19 thence over and under the idler roll 20 and thence forwardly to the harnesses. A gear 21 is fast with the roll 19 and is actuated by a pinion 22 on a shaft 23. The shaft 23 carries a ratchet wheel 24 which is actuated by a spring pressed pawl 25. This pawl 25 is pivoted to one end of a pivoted pawl lever 26 the other end of which is connected by a link 27 to a bell crank 28 pivoted at 29. This bell crank has a lost motion connection 30 with a rod 31 adjustably connected at 32 to a crank arm 33 on the beat-up motion rock shaft 34 corresponding to that in the before mentioned Merrill and Davis patents. 110

In this type of mechanism a cam lever 35 is loosely hung at its front end on the shaft 34 and carries at its rear end a roll 36 traveling in the groove 37 of the cam 38 secured to the back shaft 39. This lever 35 is arranged to be coupled to and uncoupled from the shaft 34 and during the terry weaving it remains coupled to the shaft 34 and hence the shaft is rocked back and forth every revolution of the cam 38. This cam 115 is so shaped that the shaft is rocked every full beat-up stroke of the reed or in the illustrative instance at every third forward beat of the lay. During plain weaving the lever 35 is uncoupled from the shaft so that 120 its forward end simply turns idly on the shaft which is maintained in such a position that the reed at every forward beat makes its full stroke. The mechanism by which the lever 35 is coupled to and uncoupled 125 130

from the shaft 34 as required in the operation of the loom is fully disclosed in the before mentioned Merrill and Davis patents and is under the control of the connector 16 already described.

The back shaft 39 is so timed and the cam groove 37 so shaped that at each full forward stroke beat of the reed to form the terry loops the let-off roll 19 is rotated positively to feed the terry warps forwardly. But this positive let-off roll 19 does not move to feed the terry warps forward during the partial forward strokes of the reed in terry weaving because the cam groove 37 is so shaped that no movement is given to the shaft 34 and consequently to the rod 31 during these strokes.

It will thus be seen that the positive let-off mechanism is rendered inactive during plain weaving and also during the partial forward strokes of the reed in terry weaving but is rendered active upon the full forward stroke beat of the reed for forming the terry loops.

The friction let-off is shown in detail in Figures 1 and 2 and is conveniently applied to the warp beam. For this purpose the terry warp beam 11 is provided at one head with a drum 40. A flexible friction band 41 surrounds the greater portion of the periphery of the drum and is arranged so that its tension or pressure on the drum may be adjusted as desired and so that a predetermined amount of tension or friction may be exerted during terry weaving or preferably just sufficient to prevent over-running. This friction let-off mechanism is also arranged to act during plain weaving to give any required degree of tension to the terry warps and thus produce the same tension on the terry warps as on the ground warps and in addition this mechanism is arranged to exert the normal or predetermined tension during terry weaving so as to enable the terry warps to be under the control of the positive let-off mechanism by which the terry warps are fed forward during the formation of the loops.

In the construction illustrated a bracket 42 is secured to the inner face of the standard 7 in required vertical position by bolts 43 passing through the slots 44. A rod 45 is adjustably secured by means of the set screws 46 in a boss 47 of the bracket 42 and projects transversely beneath the drum. A boss 48 is adjustably secured by means of a set screw 49 to the inner end of the rod 45 and has projecting inwardly therefrom a flat apertured head 50. A rod 51 passes through the aperture in the head 50 and has a T-shaped head 52 resting in a loop at one end of the band 41. This rod at its opposite end is threaded and provided with a thumb nut 53. A spring 54 extends between the nut 53 and the head 50.

The construction at the other end of the band 41 is similar. In this case the boss 55

is pivotally mounted at 56 on the bracket 42 and has an arm 57 projecting laterally and connected by a link 58 with the actuator 14. The boss 55 has adjustably secured therein by the set screws 59 the rod 60 carrying at 70 its inner end the boss 61 provided with a flat apertured head 62. A similar rod 63 provided with a T-shaped head engages a loop in the other end of the band 41, passes through the aperture of the head 62 and 75 carries the thumb nut 64 threaded thereon with the spring 65 interposed between the nut and the head. The boss 55 with its adjuncts thus constitutes a movable support for the end of the friction band.

The boss 55 is shouldered at 66 and this shoulder cooperates with a shoulder 67 and a sleeve fast to the bracket 42 so as to limit the upward movement of the rod 60 and the downward movement of the arm 57. Consequently there can be no strain on the actuator 14 or the pattern mechanism when these shoulders are in engagement which is the normal condition during terry weaving.

Since the direction of rotation of the terry warp beam and its drum 40 is toward the spring 54 this spring may be of less strength than the spring 65. The thumb nuts 53 and 64 enable the amount of friction applied to the drum 40 and consequently the tension on the terry warps to be adjusted as required.

It is desirable also in order to balance the construction to provide a similar normal amount or predetermined amount of friction at the opposite end of the terry warp beam 100 and for that purpose the construction shown in Fig. 4 may be employed. Therein a drum 68 similar to the drum 40 is secured to the warp beam. A flexible friction band 69 encircles the greater portion of this drum and is secured at one end 70 to a lever 71 fulcrumed at 72 on the standard 8. A rod 73 provided with a T-shaped head engages a loop in the other end of the band 69, passes through an aperture in the other end of the lever 71 and carries a thumbnut 74 threaded thereon with a spring 75 interposed between the nut and the head. This enables the tension on the band 69, and consequently the friction exerted upon the drum 68, to be adjusted as desired.

When the change takes place from terry weaving to plain weaving the riser 17 of the pattern chain raises the actuator 14 from its normal position shown in dotted lines in Fig. 1 to the full line position. Immediately through the link connection 58 the arm 57 is rocked thus suddenly compressing the spring 65 and intensifying the amount of friction applied to the drum 40. This action takes place quickly and as the drum is rotating in the direction opposite to the pull of the spring 65 the intensification of the friction is immediate so that there is no chance of a diminution in the length of terry loops and

they stand up to the full height until the zone of plain weaving begins.

Thus it will be seen that a simple and efficient construction is provided by which the terry warps are under complete control both during terry weaving and during plain weaving so that both weaves may be formed perfectly and evenly.

Having thus described the invention, what is claimed as new and desired to be secured by Letters Patent, is:

1. A terry loom comprising a terry warp beam, a friction let-off for the terry warp beam, means acting to cause said let-off to exert a predetermined amount of friction on the terry warp beam during terry weaving, automatically controlled means for changing from terry to plain weaving, and means acting simultaneously with such a change and prior to the first beat-up of plain weaving to effect a predetermined intensification of the amount of friction exerted on the terry warp beam, thereby to maintain the terry loops of uniform and full length to the end of the zone of terry weaving and to begin the zone of plain weaving perfectly.

2. A terry loom comprising a ground warp beam and means for producing the required tension on the ground warps, a terry warp beam, a friction let-off for the terry warp beam, means acting to cause said let-off to exert a predetermined amount of friction on the terry warp beam during terry weaving, automatically controlled means for changing from terry to plain weaving, and means acting simultaneously with such a change and prior to the first beat-up of plain weaving to effect an intensification of the amount of friction exerted on the terry warp beam sufficient to make the tension on the terry warps to correspond to the tension on the ground warps, thereby to maintain the terry loops of uniform and full length to the end of the zone of terry weaving and to begin the zone of plain weaving with equal tension on the terry and ground warps.

3. A terry loom comprising a terry warp beam, a friction let-off for the terry warp beam, means acting to cause said let-off to exert a predetermined amount of friction on the terry warp beam during terry weaving, means for adjusting the said predetermined amount of friction, automatically controlled means for changing from terry to plain weaving, and means acting simultaneously with such a change and prior to the first beat-up of plain weaving to effect a predetermined intensification of the amount of friction exerted on the terry warp beam, thereby to maintain the terry loops of uniform and full length to the end of the zone of terry weaving and to begin the zone of plain weaving perfectly.

4. A terry loom comprising a terry warp beam, a friction let-off for the terry warp

beam, means acting to cause said let-off to exert a predetermined amount of friction on the terry warp beam during terry weaving, automatically controlled means for changing from terry to plain weaving and vice versa, means acting simultaneously with the change from terry to plain weaving and prior to the first beat-up of plain weaving to effect a predetermined intensification of the amount of friction exerted on the terry warp beam and acting simultaneously with the change from plain to terry weaving and prior to the first beat-up of terry weaving to restore the said predetermined amount of friction on the terry warp beam, thereby to maintain the terry loops of uniform and full length throughout the zone of terry weaving and to effect perfect plain weaving throughout the zone of plain weaving.

5. A terry loom comprising a terry warp beam, a friction let-off for the terry warp beam, means acting to cause said let-off to exert a predetermined amount of friction on the terry warp beam, an actuator which acts to effect the change from terry weaving to plain weaving and vice versa, and means operated by and simultaneously with said actuator upon effecting the change from terry weaving to plain weaving and prior to the first beat-up of plain weaving to effect a predetermined intensification of the amount of friction exerted on the terry warp beam and upon effecting the change from plain to terry weaving and prior to the first beat-up of terry weaving to restore the said predetermined amount of friction on the terry warp beam, thereby to maintain the terry loops of uniform and full length throughout the zone of terry weaving and to effect perfect plain weaving throughout the zone of plain weaving.

6. A terry loom comprising a terry warp beam, a friction let-off for the terry warp beam, means acting to cause said friction let-off to exert a predetermined amount of friction on the terry warp beam during terry weaving and a greater amount during plain weaving, a positive let-off mechanism for the terry warp located between the terry warp beam and the reed, and means acting to render said positive let-off mechanism active at the full forward stroke beat of the reed in terry weaving and to render it inactive during the other forward strokes of the reed in both terry and plain weaving whereby the positive let-off acts on the terry warps upon the full forward stroke beat of the reed in forming the terry loops, the friction let-off exerts the said predetermined amount of friction and the positive let-off is inactive during the partial forward strokes of the reed in terry weaving, and the friction let-off exerts the said greater amount of friction during plain weaving.

7. A terry loom comprising a terry warp beam, a friction let-off for the terry warp beam, a positive let-off mechanism for the terry warp located between the terry warp beam and the reed, and means acting to render the positive let-off active and to cause the friction let-off to exert a predetermined amount of friction upon the full forward stroke beat of the reed for forming the terry loops, to cause the friction let-off to exert the said predetermined amount of friction and to render the positive let-off inactive during the partial forward strokes of the reed in terry weaving and to cause the friction let-off to exert a greater amount of friction and to render the positive let-off inactive during plain weaving.

8. A terry loom comprising a terry warp beam, a friction let-off for the terry warp beam, means acting to cause said let-off to exert a predetermined amount of friction on the terry warp beam, an actuator which acts to effect the change from terry weaving to plain weaving and vice versa, means operated by said actuator upon effecting the change from terry weaving to plain weaving to intensify the amount of said friction and upon effecting the change from plain weaving to terry weaving to restore the said predetermined amount of friction, and means for preventing the friction let-off from exerting any strain on the actuator during terry weaving.

9. In a terry loom, a terry warp beam, a drum rigid and concentric therewith, a frame for supporting the beam, a friction band partially surrounding the drum, a tension spring connecting one end of the band to the frame, a support movably mounted

on the frame, a second tension spring connecting the other end of the band to the support, automatically controlled means for changing from terry to plain weaving, and means acting simultaneously with such a change suddenly to move the support a predetermined distance against the tension of the second spring, thus immediately to effect a predetermined intensification of the friction exerted by the band on the drum during plain weaving.

10. In a terry loom, a terry warp beam, a drum rigid and concentric therewith, a frame for supporting the beam, a friction band partially surrounding the drum, means connecting the end of the band toward which the drum is rotated to the frame, a support movably mounted on the frame, a tension spring connecting the other end of the band to the support, automatically controlled means for changing from terry to plain weaving, and means acting simultaneously with such a change suddenly to move the support a predetermined distance against the tension of the spring thus immediately to effect a predetermined intensification of the friction exerted by the band on the drum during plain weaving.

11. In a terry loom the construction defined in claim 9 together with means for limiting the movement of the support in the opposite direction to that which it is moved to intensify the friction whereby a minimum predetermined amount of friction is exerted by the band on the drum without exerting strain on the means for moving the support.

In testimony whereof, I have signed my name to this specification.

HARRY A. DAVIS.
